(57) **CLAIM**

The ornamental design for a pullout basket, as shown and described.

DESCRIPTION

FIG. 1 is a perspective view of a pullout basket shown independent of environment for ease of disclosure only; FIG. 2 is a front elevation view thereof, shown independent of environment for ease of disclosure only; FIG. 3 is a rear elevation view thereof, shown independent of environment for ease of disclosure only; FIG. 4 is right side elevation view thereof, shown independent of environment for ease of disclosure only; and, FIG. 5 is a left side elevation view thereof, shown independent of environment for ease of disclosure only; FIG. 6 is a top plan view thereof, shown independent of environment for ease of disclosure only; and, FIG. 7 is a bottom plan view thereof, shown independent of environment for ease of disclosure only. The broken lines showing the pull out basket structure are for the purposes of illustrating environment and form no part of the claimed design.
